CLAIM

The ornamental design for an end cap, as shown and described.

DESCRIPTION

FIG. 1 is a perspective view of an end cap in accordance with a preferred embodiment of the present invention;

FIG. 2 is another perspective view of the end cap;

FIG. 3 is still another perspective view of the end cap;

FIG. 4 is yet another perspective view of the end cap;

FIG. 5 is a further perspective view of the end cap;

FIG. 6 is a top view of the end cap;

FIG. 7 is a front view of the end cap, with the rear view being a mirror image thereof; and,

FIG. 8 is a bottom view of the end cap.

The broken lines shown in the figures are for illustrative purposes only and form no part of the claimed design.
